UNITED STATES PATENT OFFICE.

JOHN J. McNAMEE, OF NORWOOD, OHIO.

BRAKE-SETTING APPARATUS FOR RAILWAYS.

No. 876,387.

Specification of Letters Patent.

Patented Jan. 14, 1908.

Application filed August 5, 1907. Serial No. 387,044.

To all whom it may concern:

Be it known that I, JOHN J. McNAMEE, a citizen of the United States of America, and resident of Norwood, county of Hamilton, State of Ohio, have invented certain new and useful Improvements in Brake-Setting Apparatus for Railways, of which the following is a specification.

The object of this invention is an electrical device for operating the brakes of a railway car which is carried by the car and which may be actuated readily by an employee, not upon the car, to set the brakes, and may then be readily reset by the engineer or motorman upon the car for throwing off the brakes and putting the car in condition for proceeding. This object is attained by the means described in the specification and illustrated in the drawings, in which,

Figure 1 is a side elevation of a locomotive engine and of a track, and of a front elevation of a signal tower, showing the brake-setting apparatus embodying my invention upon the engine, and the means for actuating the same upon the track, the switch being held open. Fig. 2 is a detail sectional view upon an enlarged scale of an electro-magnet, its armature, the valve for opening the train line and the connections between the valve and the armature. Fig. 3 is a detail elevation of the valve for opening the train line, partly in section. Fig. 4 is a plan view of the contact device which is to be located adjacent to the tracks near the signal towers. Fig. 5 shows the switch used in signal towers upon a somewhat enlarged scale and wires connecting it and the contact piece. Fig. 6 is a view of the switch taken at right angles to Fig. 5. Fig. 7 is a plan view of a part of the track showing a contact device, such as is to be located at intervals along the track. Fig. 8 is a sectional view of the switch box shown in Fig. 7, but upon an enlarged scale. Fig. 9 is a plan view of a railway switch and the contact devices to be placed upon opposite sides of the switch, at a distance therefrom, the tracks being shown broken out and brought together to economize space. Figs. 10 and 11 are detail views of the valve for regulating the rate of exhaust from the train pipe when it is opened.

The invention is illustrated as applied to a Westinghouse air-brake, wherein the brakes are set by the engineer's opening the train

pipe to allow the pressure in the same to be reduced, which reduction in the train pipe pressure actuates the air brakes.

I have placed a valve in the train line, to which is connected an arm, the rotation of which opens this valve. The arm is spring pressed so as normally to tend to open the valve, but is locked against movement by means of a lever, which may be moved to release the arm when an electro-magnet is energized. The electro-magnet and its batteries are located upon the railway car, one pole of the battery being in electrical communication with the wheels of the car, the other pole of the battery being in electrical communication with the contact piece carried by the fender or other part of the car, which is insulated from the wheels. A contact piece is placed beside the rails and has a conductor connecting it with the rails, the said conductor having located in it a switch for opening and closing it, which switch is to be controlled by an employee, not upon the car. When the contact piece upon the fender rides upon the contact piece adjacent to the rail, the electrical circuit is completed through the magnet, which thereupon is energized and will move its lever to release the arm which opens the valve in the train line and sets the brakes. If the electrical switch in the conductor between the contact piece adjacent to the rail and the rail is open, it is seen that the contact piece adjacent to the rail is not in electrical communication with the rail, and, therefore, when the contact piece upon the fender rides over the contact piece adjacent to the rail, the electric circuit of the magnet will not be closed and the brakes will not be affected.

Referring to the accompanying drawings: The train line is indicated by A, the valve for opening the train line by B. This valve is a plug valve, upon whose stem, b, is secured an arm, b', against which presses a coiled spring, b², which normally tends to rotate the valve stem, b, to open the train pipe. When opened, the train pipe will exhaust into a pipe, a, which leads into the cab and has at its upper end a plug valve, a', the degree of opening of which will control the size of the exhaust, as illustrated in Figs. 10 and 11, so as to regulate the speed with which the brakes will be set. Pipe, a, is positioned so that when the valve, B, is

opened, the exhaust will blow against the engineer and apprise him of the fact that the valve, B, has been opened.

Arm, b', is held in position to close the valve, B, by means of a bell-crank lever, c, which is pivoted at, c', upon a box, c², which is hung by brackets, c³, from the pipe, A', which leads to the air reservoir. The box, c², is hung from the reservoir pipe, A', simply as a matter of convenience, since in locomotive engines this pipe is usually located in a position adjacent to the cab-steps, A², so that the engineer after the valve, B, has been opened, may readily set the arm, b', in its normal position to again close the same.

The bell crank lever, c, is connected by a link, d, with the armature, d', of an electro-magnet, D, which is mounted within the box, c². The armature, d', is pivoted at, d², to the magnet and when the bell-crank lever, c, is in position so that its hook, c⁴, takes under the arm, b', the armature, d', is out of contact with the poles of the magnet, D, and when the magnet is energized and draws the end, d³, of the armature upward, the bell-crank lever, c, is rotated about its pivot and draws the end, c⁴, from beneath the arm, b', permitting the spring, b², to open the valve, B. The coils of the magnet, D, are connected to an electric battery, E, which is located upon the railway car, or engine. Upon each side of the fender, a³, of the engine is carried a contact piece, e, which is connected by wire, e', to one pole of the battery, E, the other pole of the battery is connected to the axle, A⁴, of the truck of the engine by a wire, e². Wire, e', is illustrated as passing around the coils of the electro-magnet before extending to the contact piece upon the fender.

I have illustrated three forms of electrical switches for connecting the track with the contact pieces to be placed adjacent to the track, viz., one form to be used in signal stations and to be controlled by the operator, another form to be placed adjacent to the track switches and to be affected by the position of the switch, and a third form to be located at intervals alongside the tracks and to be operated by an employee where it is desired to stop the train for any reason, such as, for instance, where another train has become stalled from any reason. The contact pieces consist of wooden blocks, F, placed parallel to the tracks, T, and bearing upon their upper faces contact strips, f, which stand above the level of the tracks, T. The contact piece, f, is connected by a wire, f', with a switch contact, f², and rail, T, is connected by a wire, f³, with the other switch contact, f⁴. The form of connection between the contact strip, f, and the contact pieces, f², f⁴, and the track are the same for the form of electric switch used in signal towers,

and that alongside the track as illustrated in Figs. 4, 5, 6, and 7 and 8.

In the form of switch used in signal towers, the switch lever, f⁵, is held normally in contact with the contact pieces, f², f⁴, by means of a spring, f⁶. Wire, f', leads from contact piece, f, to the contact point, f², of the switch in the tower and wire, f³, leads from the rail to the contact piece, f⁴, of the electric switch in the tower. In this form it is seen that normally communication between the contact strip, f, and the rail, T, is unbroken and that unless the operator in the tower holds the switch-lever, f⁵, open, when the contact piece, e, upon the feeder rides over the contact strip, f, the circuit through the magnet, 80 D, will be completed, that is, through the wire, e', the contact piece, e, contact strip, f', wires, f', contact pieces, f², f⁴, wire, f³, rail T, axle, a², and wire, e², thereby energizing the magnet, raising its armature, d', throwing 85 the bell-crank lever, c, and allowing the arm, c⁴, to open the valve, B. If, therefore, the operator is notified to stop the train, he does so by not opening the switch, f⁵. Or, if the operative be inattentive to duty from any 90 reason, the train will be stopped, because unless positively actuated by the operator in the tower, the contact strip will be in communication with the rail, T, and will therefore complete the circuit when contacted by the piece, e.

In the form of switch used at points alongside the track, the switch-lever, f⁹, stands normally open, so that unless positively actuated to close the communication between the contact pieces, f², f⁴, the contact strip, f, is not in communication with the rail, T, and the electrical circuit will not be closed when the contact piece, e, rides over the strip, f. However, when an employee desires to 105 stop a train between stations, he may do so by opening the lock, f¹⁰, of the box, f¹¹, in which the switch-lever, f⁹, is located and throw the switch so as to complete the communication between the contact piece, f, 110 and the rail, T. For instance, if a train should become wrecked or stopped from other causes upon a track, the brakeman would go back to the next switch-box, f¹¹, would open the lock, f¹⁰, and throw the 115 switch-lever, f⁹, into contact with the contact studs, f², f⁴, so that the next train which came along would be stopped by having its brakes thrown on automatically.

In the form used for track switches, switch 120 f⁹, stands normally open but wires, f⁷, and f⁸, lead from contact strips, f, upon opposite sides of the switch to a contact strip, f¹³, which is secured to one of the ties between the tracks, and the track, T, has a wire, f¹⁴, 125 connecting it to a contact piece, f¹⁵, carried by the switch-rod, G. The contact piece, f¹⁵, is located upon the rod, G, in a position

such that when the switch is closed, as illustrated in Fig. 9, the contact pieces, f^{15}, f^{13} , are out of contact with each other, but when the switch is open, or partly opened, the contact piece, f^{15} , contacts the contact piece, f^{13} , thereby completing the communication between the rail, T, and the contact piece, f . The contact pieces, f , are to be located upon each side of the switch, g , say 10 about four hundred feet, or more distant therefrom. Should a switch, therefore, be left open, or partly open, when the train came within four hundred feet or so from the switch, since the contact strip, f , is in communication with the rail, T, the brakes would be thrown on and the train stopped.

What I claim is:

1. In combination with a railway car air brakes located upon the car, a valve carried by the air-brakes and the opening of which actuates the air-brakes, an arm connected to the valve for opening and closing the same, an electro-magnet secured upon the car, an armature mounted adjacent to the magnet so as to be moved thereby when the magnet is energized, means for conveying the movement to the armature of the arm to open and close the valve, a source of electrical energy located upon the car, an electrical contact piece carried by the car adjacent to the tracks and insulated from the wheels of the car, a broken circuit leading from the source of energy in which circuit the electro-magnet is placed, one end of the circuit being connected to said contact piece and the other end being in communication with the wheel of the car, a contact device adjacent to the track and adapted normally to complete electrical communication between the track and the contact piece on the car when the car passes over said contact device and a means whereby an operator may prevent the completion of said communication.
2. In combination with a car having air-brakes, a valve connected to the air-brake the opening of which actuates the same, an arm connected to the valve for opening and closing it, an electro-magnet secured upon the car, an armature mounted adjacent to the magnet to be moved thereby when the magnet is energized, means for conveying the movement of the armature to the arm to open the valve, a source of electrical energy located upon the car, an electrical contact piece carried by the car adjacent to the tracks and insulated from the wheels, a broken circuit leading from the source of energy, in which circuit the electro-magnet is placed, one end of the circuit being connected to the contact piece and the other end being in communication with a wheel of the car, a second electrical contact piece

placed adjacent to the track in the path of the contact piece upon the car, a conductor 65 for connecting the second contact piece with the track and a switch located in said conductor for making and breaking the circuit.

3. In combination with a car having air-brakes, a valve connected to the air-brake 70 the opening of which actuates the same, an arm connected to the valve for opening and closing it, an electro-magnet secured upon the car, an armature mounted adjacent to the magnet to be moved thereby when the 75 magnet is energized, means for conveying the movement of the armature to the arm to open the valve, a source of electrical energy located upon the car, an electrical contact piece carried by the car adjacent to 80 the tracks and insulated from the wheels, a broken circuit leading from the source of energy, in which circuit the electro-magnet is placed, one end of the circuit being connected to the contact piece and the other 85 end being in communication with a wheel of the car, a second electrical contact piece placed adjacent to the track in the path of the contact piece upon the car, a conductor for connecting the second contact piece with 90 the track, a switch located in said conductor, an automatic means for holding the switch in a position normally to close said conductor and a means actuated by an operator for throwing the switch to open the said 95 conductor.

4. In combination with a locomotive engine Westinghouse air-brakes upon the engine, a valve located in the train pipe the opening of which applies the brakes, an 100 arm carried by the valve the movement of which opens and closes the valve, an electro-magnet upon the engine, an armature pivoted upon the magnet, a lever for holding the arm of the valve in its closed position, 105 a means for connecting the lever and the armature whereby the movement of the armature toward the magnet releases the arm to open the valve, a contact piece carried by the fender and insulated from the 110 wheels of the engine, an electric battery carried by the engine, a broken circuit leading from the battery in which the armature is included, one of the broken ends of said circuit being connected to the contact piece on the tender and the other end of the circuit being connected to a wheel of the engine, a contact strip mounted adjacent to the rails, a conductor connecting the strip with the rails, and a switch interposed in 120 the conductor for making and breaking the conductor.

JOHN J. McNAMEE.
